(No Model.)

B. H. HASKINS.

AUTOMATIC SPITTOON HOLDER.

No. 286,299.

Patented Oct. 9, 1883.

by Franklin Scott, Atty.

UNITED STATES PATENT OFFICE.

BENJAMIN H. HASKINS, OF MECHANICSVILLE, NEW YORK, ASSIGNOR OF
ONE-HALF TO JOHN YOUNG, OF SAME PLACE.

AUTOMATIC SPITTOON-HOLDER.

SPECIFICATION forming part of Letters Patent No. 286,299, dated October 9, 1883.

Application filed September 1, 1883. (No model.)

To all whom it may concern:

Be it known that I, BENJAMIN H. HASKINS, of Mechanicsville, in the county of Saratoga and State of New York, have invented certain Improvements in Automatic Spittoon-Holders, of which the following description, in connection with the accompanying single sheet of drawings, constitutes a specification.

This invention relates to spittoons adapted for use in churches, public halls, and especially in railway-carriages, and is designed to be generally located beneath the seat and to be manipulated with the foot of the person using it. Its construction and mode of operation are apparent from the accompanying drawing, which shows my invention as applied beneath the seat of a passenger-coach.

The devices constituting the essential parts of my apparatus are mounted upon or attached to a small table, B, upon the top of a standard, A, which standard is fastened to the floor of the car beneath the center of the car-seat. Upon table B may be mounted apparatus for carrying one or two spittoons, as may be desired. For railway-passenger-coach use, two sets are preferable. Table B may be made vertically adjustable in standard A to accommodate it to the varying heights of foot-rails in different kinds or makes of cars, and in practice I prefer to make them so.

Upon the top of table B are two broad flat-headed pivot-studs, C C, about one or the other of which the spittoon-lever E vibrates. Intermediate between these is erected the post D, connected with which is an adjustable eye or hook, L, which serves for the attachment of one end of the retractile spring S, the other end of which is attached to pin k at some point on the lever E. The office of spring S is to draw lever E back into place after it has been thrown around for use, and to maintain the spittoon in a central position beneath the car-seat when it is not wanted for use.

The general figure of the spittoon-lever is that of a T, and near each end of the outside edge of the cross-head it is recessed, as at R R. These recesses are fitted to engage and co-operate with pivot-studs C C. Upon some part of lever E near the cross-head, or upon the same, are attached the two toe-pieces H H, which provide the means whereby the lever is

actuated or manipulated. These may be made adjustable as to their vertical and lateral projection, if so desired, or may be made solid with lever E. Lever E is provided at its outer end with a holder or clamp, F, for retaining the spittoon G, which clamp is adapted to slide upon or be otherwise adjustable as to its position on lever E. This provision is to meet the requirement of contracted space under narrow seats or otherwise.

T T are the foot-rails, and table B is vertically adjusted in reference to them, so as to bring the toe-pieces H H at such an elevation as will most conveniently accommodate the user, and at the same time permit lever E to be swung freely around over the rails T T.

Two small guards, P P, or one for each pivot-stud C, are provided to prevent the lever E from being detached from the stud, about which it is rotating, by reason of any external blow or accident.

This mechanism is operated by the foot of the passenger sitting in the adjacent seat. When two spittoons are mounted on one stand, as in railway practice, accommodations are afforded for the use of the passenger occupying each end of the seat. In halls and churches the spittoons would probably be mounted singly.

The operation of the invention is as follows: The stand A being fixed in position beneath the seat, and the elevation of table B adjusted as desired, spring S by its retractile force draws lever E around so as to bring both recesses R R under pivot-studs C C, so that they find a bearing against the same. This brings arm Y of lever E in a central longitudinal position beneath the seat, or between foot-rails T T. If it is desired to use the spittoon, the passenger, resting his foot on the foot-rail, as shown, presses against toe-piece H with the edge of his foot, as shown in the drawing, and thus causes lever E to rotate around pivot-stud C sufficiently to swing the spittoon around in front of him, between his feet, into a position convenient for use, after which the spring S will return the spittoon to its dormant position under the seat and out of the way. The apparatus is susceptible of the like manipulation by the sitter occupying the seat on the opposite side.

In the drawing I have shown but one set of devices mounted on a table and the table

broken away; but it is obvious that two similar sets, or a right and a left hand set, may be mounted on the same table, which is my design with reference to railway passenger-coaches; hence

I claim as my invention—

1. The described apparatus for automatically operating a spittoon-holder, consisting of a standard and table for supporting the spittoon-holding device, two pivot-studs erected thereon, a T-shaped lever for carrying the spittoon, the head of such lever having provisions at either end thereof for engaging with and rotating about one of the said pivot-studs, and the outer end of said lever having provisions for holding a spittoon, and armed with the described toe-pieces, in combination with means, substantially as shown, for automatically

returning the spittoon to its dormant position after use, substantially as described and set forth.

2. An automatic spittoon-holder for use in railway-carriages, located beneath the seat in a plane at or near the level of the foot-rail, adapted to be operated by the foot resting on the foot-rail, and also to be operated in like manner from either side of the seat, substantially in the manner described, and for the purposes set forth.

In testimony whereof I have hereto subscribed my name this 28th day of June, A. D. 1883.

BENJAMIN H. HASKINS.

In presence of—

FRANKLIN SCOTT,

WILLIS H. PHILLIPS.
